[57] CLAIM

The ornamental design for low profile lever-off plug, as shown and described.

DESCRIPTION

FIG. 1 is a perspective view from the top, front, right side of a low profile lever-off plug showing our new design; FIG. 2 is a plan view from above thereof; FIG. 3 is a plan view from below thereof; FIG. 4 is a right side elevation thereof, the left side elevation being a mirror image thereof; FIG. 5 is a front elevation thereof; and, FIG. 6 is similar to FIG. 2, but shows an alternative form of our design; except for the appearance of the strain reliever and the angle at which this meets the plug body, all aspects of the alternative form are the same as those seen in FIGS. 1-5.

In the drawings, surrounding structure not forming a part of our design is shown in dashed outline.
